UNITED STATES PATENT OFFICE.

JAMES M. BLACKBURN, OF BALTIMORE, MARYLAND.

STRETCHER FOR TROUSERS, BELTS, &c.

No. 873,026.

Specification of Letters Patent.

Patented Feb. 11, 1908.

Application filed September 14, 1907. Serial No. 392,880.

To all whom it may concern:

Be it known that I, JAMES M. BLACKBURN, a citizen of the United States, and resident of Baltimore, Maryland, have invented certain new and useful Improvements in Stretchers for Trousers, Belts, &c., of which the following is a specification:

The object of the present invention is to produce a cheap, simple and effective 10 stretcher for flat articles, such as trousers and belts.

The invention comprises broadly a pair of rods of steel or other suitable metal and a pair of clamps, one of which is preferably 15 rigidly connected with the rods, while the other is slidably connected and adapted to be held in any desired position by gripping devices.

When the invention is used as a trousers 20 stretcher the adjustable clamp is arranged to move freely away from the fixed clamp and to be automatically prevented from moving toward the fixed clamp by the gripping devices. On the other hand, when the 25 invention is used as a belt stretcher to draw together the ends of a belt which is to be sewed while it is mounted on its pulleys, the movable clamp is arranged to slide freely on the side rods in moving toward the fixed 30 clamp while the gripping devices prevent it from moving backward or away from the fixed clamp.

Referring to the accompanying drawing, 35 Figure 1 is a side view of a trousers stretcher embodying the invention and adjusted to stretch a pair of trousers; Fig. 2 is an enlarged end view of the adjustable clamp shown in Fig. 3; Fig. 3 is a section on the line 3 of Fig. 1; Fig. 4 is a side view of the gripping device shown in Fig. 3, the cover plate being removed; Fig. 5 is a perspective view 40 illustrating the construction of the clamp for securing the garment in the stretcher; Fig. 6 is a view showing the manner of folding the 45 stretcher; Fig. 7 is a sectional view of one of the joints in the side rods; Fig. 8 shows a form of the invention in which the side rods are not jointed; Fig. 9 shows the invention embodied in a belt stretcher; Fig. 10 is an 50 end view of one of the clamps shown in Fig. 9; Fig. 11 is a perspective view showing the manner in which the two parts of the clamp interlock; and Fig. 12 is a sectional view of 55 part of one of the clamps illustrating on a larger scale the gripping device shown on Fig. 3.

Referring to Figs. 1 to 8 of the drawing, A indicates the fixed clamp of a trousers stretcher, B the adjustable clamp and C the side rods connecting the clamps and upon 60 which the clamp B is adjustable. The rods C are preferably constructed of spring steel having considerable flexibility but stiff enough to produce the necessary strain to stretch a pair of trousers without buckling. 65 Each side rod may be a single piece, as shown in Fig. 8, or two pieces hinged together, as shown in Figs. 1, 6 and 7. In these latter figures the two parts of the side rod are connected by a link 1 which permits them to be 70 doubled one upon the other, as shown in Fig. 6, and they are provided with a close fitting tube 2 which is adapted to slip over the hinge joint and hold the two sections of rod in alignment, as shown in Fig. 7. Any other 75 suitable hinge joint may be substituted for that shown in the drawing.

The adjustable clamp B comprises a cross bar 3 having perforations through which the rods C pass and having at each end a recess 4 to receive a gripping device adapted to hold the clamp in any desired position upon the rod. The gripping device which I prefer to use on account of its simplicity, cheapness and effectiveness is illustrated in Figs. 3 and 85 4.

Referring to these figures, 5 indicates a disk surrounding the rod. At one side the disk is supported by a shoulder 6 on the bar 3 of the clamp and on the other side a spring 7 is provided which presses the disk against 90 the shoulder 6, tending to tilt the disk about the shoulder as a fulcrum. On the side of the rod opposite the fulcrum 6 is a push pin 8 which extends through the wall of the recess 4, the outer end projecting so as to be conveniently engaged by the hand and the inner end being adapted to engage the disk 5 and press the same against the spring 7. It will be understood that there is a like gripping device at each end of the main clamp B. The 100 clamp B comprises the bar 3 and a shorter bar 9 between which the trousers are gripped, the two being connected by suitable bolts 10 provided with thumb nuts 11. One of the bars, for instance the bar 3, is provided with 105 a recess 12, at the middle to receive the seams of the trousers which would prevent the proper clamping of the trousers if both bars were straight. The bar 3 is otherwise slightly arched from the ends of the bar 9 to 110 the recess 12, so that the bar 9 will be sprung slightly as the bolts 10 are tightened, as

shown in Fig. 2. Adjacent to each of the bolts 10 the bar 3 is provided with a diagonal shoulder 13 against which the diagonal end 14 of the bar 9 is adapted to bear, as shown in Fig. 5. The bar 9 is provided at each end with a notch 15 to receive the bolt 10 and the bar 3 is provided with a complementary notch 16. A washer 11^a is preferably provided as a bearing for the thumb-nut 11 and a spring 10^a is provided to lift the washer when the thumb-nut is released.

The clamp A is constructed exactly like the clamp B except that the gripping devices illustrated in Figs. 3 and 4 are omitted. The side rods C, pass through openings in the clamp A and are prevented from sliding through said clamp by fixed nuts or collars 17 arranged on opposite sides of the clamp. The rods C may be otherwise suitably connected with the clamp A, it being only necessary that they should be rigidly connected with said clamp.

The operation of the invention illustrated in Figs. 1 to 8 inclusive, is as follows: The trousers are clamped between the bars 3 and 9 of each of the clamps A and B, as illustrated in Fig. 1, the seams being arranged in the recesses 12. The clamp A is then held stationary and the clamp B pulled away from it until the proper tension is placed upon the trousers. The clamp B will slide freely on the rods C toward the ends of said rods but is prevented from moving backward by the gripping disks 5 which are canted by the spring 7 and shoulder 6, and tend at all times to grip the rods securely when the clamp B is drawn toward the clamp A. Owing to the flexibility of the rods C it is not essential that the clamps A and B should be always parallel. If it is desired to put one edge of the pantaloons under greater tension than the other it can be done by pulling the corresponding end of the clamp B farther away from the clamp A. While the trousers are stretched, as illustrated in Fig. 1, they may be placed on a table or ironing board and ironed, the stretcher being so arranged that it will not interfere with this operation. To release the strain upon the trousers it is simply necessary to press in the push pins 8 until the gripping disks 5 are at right angles with the rods C. When in this position the clamp B can be moved freely in either direction upon the rods C. The disks 5 are especially useful as gripping devices as they cannot get out of proper position when once placed on the rods, being symmetrical. They are also especially cheap to manufacture. For ordinary home use I prefer the single side rods shown in Fig. 8 as they are simpler and cheaper and less liable to get out of order than the jointed rods, but for stretchers which are required to be transported in trunks or other receptacles, it is desirable to

use the jointed rods, such as are illustrated in Figs. 1, 6 and 7.

In Figs. 9 to 12 inclusive, I have illustrated my invention in the form of a belt stretcher, that is, a stretcher adapted to bring the two ends of the belt into suitable position for uniting them by sewing or otherwise. In these views I have also shown a modified form of clamp which is somewhat simpler in construction than that shown in the preceding figures and which I have found to be very effective for gripping belts or other flat objects. Referring to these figures, A and B indicate the clamps and C the side rods. Each clamp consists of a base piece 20 having handles 21 at its ends and a relatively movable piece 22 which cooperates with the part 20 to grip the article to be stretched. The base piece 20 has a recess 23 to receive the part 22 and at each end of this recess there is an inclined groove 24 adapted to receive a correspondingly inclined tongue 25 on the part or jaw 22. The grooves and tongues 24, 25, are so inclined that the pull upon the belt or other object tends to move the jaw 22 farther into its recess 23, and thus the greater the pull upon the object the tighter it is gripped. It will be obvious that the tongues and grooves on the parts A, B, in the belt stretcher should be inclined in opposite directions as the ends of the belt pull in opposite directions. It will also be obvious that when this form is used as a trousers stretcher the inclinations of the tongues and grooves of the clamps are the reverse of the inclination in a belt stretcher.

In the belt stretcher illustrated the rods C, C, are rigidly connected with the clamp A and adjustably connected with the clamp B, the latter clamp being provided with gripping devices which may be similar to those shown in Figs. 3 and 4. In Figs. 9 and 12 however I have shown a slightly modified arrangement of the gripping devices. Referring to these figures 26 indicates a disk having a round opening through which the rod C passes freely when the disk is at right angles to the rod, but in which the rod fits so closely that it is gripped when the disk is slightly canted, as shown in Fig. 12. The disk is located in a recess 27 which is formed in the body of the clamp and normally closed by a cover plate 28. A transverse pin 29 forms a fulcrum about which the disk is normally canted by a spring 30 so that the rod C is normally gripped when the stretcher is in use. A push button 31 is provided for bringing the disk into a plane at right angles with the rod when desired. The operation of this gripping device is the same as the operation of the gripping devices shown in Figs. 3 and 4.

The operation of the invention when used as a belt stretcher is as follows: It is assumed that the belt X, is mounted on its pulleys 130

and that the ends are to be drawn together and held in position for connecting them. This is accomplished by securing one end of the belt in the clamp A and the other end in 5 clamp B and then moving the clamps toward each other by means of handles 21. The two pairs of handles may be operated simultaneously by two persons or the handles on one side may be operated alternately with 10 those on the other by a single person. When the clamp B is moved toward the clamp A the rods C slide freely through the gripping devices but said devices prevent any backward movement until the push buttons are 15 pressed in to release them.

It will be evident that when the invention is used as a belt stretcher the rod C need not be of elastic material, but they are preferably stiff steel rods substantially the same as are 20 used in the trousers stretcher.

Having described my invention what I claim and desire to secure by Letters-Patent is,

1. A stretcher for flat articles comprising 25 a pair of clamps adapted to hold the article to be stretched, and a pair of metal rods connecting the respective ends of said clamps, the rods being rigidly connected with one of said clamps and being adjustably connected 30 with the other clamp, and gripping devices upon the latter clamp for engaging said rods, the gripping devices each consisting in a metal disk through which the rod passes, a spring for canting said disk upon the rod, 35 and means for compressing the spring to release the rod from the disk.

2. A stretcher for flat articles comprising a pair of clamps adapted to hold the article to be stretched, and a pair of metal rods connecting the respective ends of said clamps, the rods being rigidly connected with one of 40 said clamps and being adjustably connected with the other clamp, and gripping devices

upon the latter clamp for engaging said rods, the gripping devices each consisting in a 45 metal disk through which the rod passes, a spring for canting said disk upon the rod, and a push pin mounted in the clamp and arranged to bear upon the disk to compress the spring and release the rod from the disk. 50

3. A stretcher for flat articles comprising a pair of clamps adapted to hold the article to be stretched, and a pair of flexible metal rods connecting the respective ends of said clamps, the rods being rigidly connected with one of 55 said clamps and being adjustably connected with the other clamp, and gripping devices upon the latter clamp for engaging said rods.

4. A stretcher for flat articles comprising a pair of clamps adapted to hold the article to be stretched, and a pair of metal rods connecting the respective ends of said clamps, the rods being rigidly connected with one of 60 said clamps, and being adjustably connected with the other clamp, and gripping devices 65 upon the latter clamp for engaging said rods, the said rods being jointed and adapted to be folded and provided with sleeves for holding the sections of the rods in alinement.

5. In a stretcher for flat articles, the combination with the clamps and the side rods connecting the ends of said clamps, of the gripping devices for preventing backward movement of one of the clamps on the rods, 70 said gripping devices each comprising a perforated disk surrounding a rod, a shoulder on the clamp forming a fulcrum for said disk, a spring for canting said disk about the fulcrum, and a push pin for releasing the disk. 75

In testimony whereof I affix my signature 80 in presence of two witnesses.

JAMES M. BLACKBURN.
